CLAIM

The ornamental design for a carton, as shown and described.

DESCRIPTION

FIG. 1 is a top perspective view of the carton, showing my new design;

FIG. 2 is a right side view of the design illustrated in FIG. 1;
FIG. 3 is a left side view of the design illustrated in FIG. 1;
FIG. 4 is a rear view of the design illustrated in FIG. 1;
FIG. 5 is a front view of the design illustrated in FIG. 1;
FIG. 6 is a top view of the design illustrated in FIG. 1; and,
FIG. 7 is a bottom top view of the design illustrated in FIG. 1.
The broken lines in the drawings are for the purpose of illustrating unclaimed portions of the carton and form no part of the claimed design.

1 Claim, 4 Drawing Sheets
